RADIO CIRCUITS

Application filed October 25, 1929. Serial No. 402,378.

This invention relates to radio circuits, and more particularly to circuits including vacuum tubes.

In some circuits including vacuum tubes the nature of the tube or the nature of the circuits cooperating therewith is such that the tube is characterized by a constant apparent input capacitance. With such a circuit there is a tendency for the efficiency to fall off at the high end of the working range of frequency, owing to the decreased reactance of the tube input capacitance at high frequencies, there being, ordinarily, substantial impedance in the supply circuit. One object of our invention is to overcome this tendency and to compensate for the loss in gain at the higher frequencies so as to level the gain curve. For this purpose we connect in series with the input circuit of the tube an inductance which preferably is made of suitable magnitude to series resonate with the apparent tube input capacitance at the high end of the frequency range. The series resonant decrease in impedance or short circuit causes greatly increased current to flow, which increases the potential across either of the two series resonant reactances, and the resulting resonant rise in potential is impressed upon the tube input electrodes, which are connected across one of the series resonant reactances.

The manner in which an ordinary three electrode tube is given a constant apparent input capacitance may be, as in the case of a detector tube, by shunting the output circuit with respect to radio frequency energy, so that there is a negligible output impedance for such energy. Another example is a vacuum tube made reactionless by a special output circuit including a regenerative feed back inductance and a degenerative feed forward resistance arranged in the manner described in a patent to Lester L. Jones, No. 1,713,132, issued May 14, 1929, and in his copending application, Ser. No. 397,632, filed Oct. 5, 1929. Also, a tube may be given a constant apparent input capacitance by reason of the construction of the tube itself, a common example being the screen grid vacuum tube, in which a fourth electrode prevents capacitive coupling between the control electrode and the anode

of the tube. The present invention is generically applicable to all of the various foregoing and other similar arrangements.

While our invention is most conveniently applicable to the input circuit of a tube having a constant apparent input capacitance it is not limited thereto for the inductance may be selected to series resonate with what value of input capacitance the tube has at the frequency at which resonance is desired. For example, our invention may be applied to the input circuit of an automatically tuned tube, the inductance being designed to series resonate with the small apparent input capacitance of the tube at the high frequency end of the range. Also, when dealing with a tube which is automatically tuned over only the lower frequency portion of a relatively great frequency range, as is disclosed in a copending application of Lester L. Jones, Ser. No. 397,633, filed Oct. 5, 1929, the input capacitance is nearly constant over the high frequency portion of the range, and a series inductance may be used which series resonates with this capacitance for high frequencies.

The vacuum tube stage so far considered may in many or most cases be coupled to the output circuit of a preceding amplifier tube. If the amplifier tube output impedance is of the optimum value for maximum amplification the overall percentage increase in gain is not so great when applying our invention to the succeeding tube because the gain in the amplifier tube is apt to be reduced at high frequencies inasmuch as the series resonance of the input circuit of the succeeding tube will shunt or short circuit the output circuit of the first tube and reduce its impedance. Our invention more than makes up for this loss, giving a net gain, but the initial gain being high, the relative or percentage increase in gain may not be very high. However, in many instances the amplifier tube may for other reasons be advantageously equipped with an output impedance which is low relative to the optimum impedance, and to such a circuit our invention results in a high relative or percentage increase in gain, because the reduction in

55

75

80

85

90

95

100

gain in the amplifier tube is of little consequence, while the increase in potential applied to the second tube is relatively substantial, the initial gain not being very high.

5 A more specific object of our invention, therefore, is to apply our series inductance to a circuit including a tube following an amplifier tube having an output impedance which is less than the impedance value giving maximum amplification. The amplifier may, for example, be a screen grid tube, the tube itself having a very high impedance which is difficult to match, or it may be an automatically tuned stage wherein, to obtain 10 automatic tuning the output impedance is made less than the optimum, particularly for high frequencies.

Automatic tuning is disclosed in the patent of Lester L. Jones, No. 1,673,287, issued 20 June 12, 1928, which describes how, for this purpose, the output circuit of the tube is made naturally resonant to a frequency lower than the working frequency range. The output circuit is therefore characterized by 25 decreasing impedance with increasing frequency, which causes decreasing apparent input capacitance for the tube, and this change in capacitance may be utilized for automatic tuning of the input circuit to the received 30 frequency. Obviously, the frequency range over which a single tube may be automatically tuned depends largely upon the range of capacitance variation obtainable across the input circuit of the tube.

35 A further object of the present invention is to increase the available range of automatic tuning in such an automatically tuned stage.

The automatically tuned stage is followed 40 by another tube stage, and in most cases by a stage in which the tube has a constant apparent input capacitance, as, for example, a detector tube, or a reactionless link stage between cascaded automatically tuned amplifier 45 stages, for with such a subsequent circuit the output circuit of the automatically tuned stage may readily be kept naturally resonant to a constant frequency lower than the working frequency range. In accordance with 50 the present invention an additional inductance is connected in series with the input circuit of the succeeding tube which series resonates with the apparent tube input capacitance at high frequencies, short circuiting 55 the output circuit of the automatically tuned stage, thereby greatly reducing the output impedance and therefore the gain in the tube itself, (though not in the complete stage), and correspondingly decreasing the 60 apparent input capacitance of the automatically tuned tube. This increases the total capacitance variation available for automatic tuning, and so increases the possible range of automatic tuning.

65 To the accomplishment of the foregoing

and further objects which will hereinafter appear, our invention consists in the circuit elements and their relation one to the other as hereinafter are more particularly described in the specification and sought to be 70 defined in the claims. The specification is accompanied by drawings in which:

Fig. 1 is a wiring diagram showing the application of our invention to a detector tube;

Fig. 2 is a wiring diagram showing the application of our invention to a tube made reactionless by a special output circuit;

Fig. 3 is a wiring diagram showing the application of our invention to the input circuit of an automatically tuned amplifier 80 stage;

Fig. 4 is a wiring diagram showing the application of our invention to a screen grid tube;

Fig. 5 is a wiring diagram for an untuned 85 screen grid cascade amplifier embodying our invention;

Fig. 6 is a fictitious circuit equivalent to one with a transformer having leakage flux;

Fig. 7 is a wiring diagram showing the application of our invention to a tube following 90 an automatically tuned stage;

Fig. 8 is a graph showing the improvement 95 in the gain curve resulting from the use of our invention;

Fig. 9 is a graph explanatory of additional advantages obtainable by the use of our invention; and

Fig. 10 is a schematic wiring diagram for a 100 radio receiving system of the pre-selector and automatically tuned type embodying our invention.

Referring to Fig. 1 there is a detector tube 2 which, in the present case, is given an 105 asymmetric characteristic in order to obtain rectification by means of a biasing battery 4. The output circuit of the detector tube includes a filter stage 6 for separating the radio and modulation frequency components, this 110 filter circuit including radio frequency bypass condensers 8 and 10 and a radio frequency choke 12. The output circuit of the tube 2 consequently has negligible impedance with respect to radio frequency energy, and the apparent tube input capacitance, represented by the dotted condenser 20, therefore 115 has a small and constant value at radio frequency. Modulated radio frequency energy is applied to the input circuit of the tube 2 by any suitable coupling means, exemplified in 120 the present case by the transformer 22.

If the frequency of the carrier energy is varied from a relatively low to a relatively high frequency the capacitance 20 is decreased in reactance, and there is a tendency 125 for the potential on the control electrode of the tube to diminish, there being, ordinarily, substantial impedance in the supply circuit. Now, in accordance with our invention, an additional inductance 30 is connected in series 130

with the input circuit of the tube, and is preferably so dimensioned that it series resonates with the capacitance 20 at the high frequency end of the range, thereby shunting the transformer 22 with a negligible impedance, and causing an augmented current flow which causes a resonant rise in potential across either of the series resonant reactances. The control electrode and cathode 15 of the tube 2 being connected across one of the series resonant reactances, the condenser 20, has applied thereto the maximum available potential, so that the potential is boosted at the high frequencies, as is desired.

Attention is now directed to Fig. 2 in which there is a three electrode vacuum tube 32, the output circuit of which is selected in accordance with the teachings of Patent No. 1,713,132, aforementioned in order to make 20 the tube reactionless and to cause it to have a constant apparent input capacitance. To this end the output circuit is provided with an inductance 34 of such magnitude that it is naturally resonant to a frequency higher 25 than the working frequency range. For frequencies in the working frequency range it is therefore effectively inductive and causes a regenerative or feed back reaction through the tube 32. In series with the inductance 34 there is connected a resistance 36 which causes 30 a feed forward of energy from the input to the output circuit of the tube, and this feed forward may be adjusted to neutralize for the feed back caused by the inductance 34, so as to obtain a substantially reaction free 35 stage. The impedance of circuit 34, 36 may be increased to raise the gain in tube 32, in which case as additional refinements a capacitance 38 may be connected in parallel with 40 the resistance 36, and a succeeding vacuum tube stage may be arranged to have an apparent input capacitance suitable for perfecting the reactionlessness of tube 32, all in accordance with the teachings in the copending application of Lester L. Jones, Ser. No. 45 397,632, aforementioned.

In such a special reaction free stage the apparent tube input capacitance, here indicated by the dotted condenser 20, remains substantially constant, and it is therefore convenient to apply our invention thereto, which is done by the simple addition of an inductance 30, the magnitude of which is 50 preferably selected to series resonate with the capacitance 20 at the high end of the frequency range.

Our invention is not restricted to use with a tube having a constant apparent input capacitance. This is illustrated by Fig. 3, 55 in which the tube 202 is provided with an input circuit including a preferably bifilar coupling transformer 204 and an inductance 30 connected in series therewith. The output circuit of tube 202 includes a preferably bifilar transformer 206 so dimensioned as

to cause the apparent input capacitance 21 of tube 202 to vary over a considerable range. Transformer 204 and inductance 30 may be selected to keep in resonance with the capacitance 21 over most of the working frequency range while inductance 30 may be selected to series resonate with capacitance 21 at a still higher frequency, thereby improving the gain in the amplifier tube over a broader range than would otherwise be possible. Tube 202 might in some cases be intentionally arranged to tune over only the lower frequency portion of the complete frequency range, for reasons which are set forth more in detail in the copending application of Lester L. Jones, Ser. No. 397,633, already referred to, explaining how automatically tuned stages may be coupled directly in cascade. In such a case the apparent input capacitance 21 of the tube is nearly constant in the high frequency portion of the complete frequency range, but the invention has been applied to a tube having a very widely varying input capacitance.

In Fig. 4 we have illustrated the application of our invention to a tube of the screen grid type. The tube 52 comprises not only the usual cathode, anode, and control electrode, but also a screen grid 54 which shields the anode from the control electrode and cathode, and prevents exposure of the control electrode of the tube to the alternating potential on the anode of the tube, and in consequence the apparent input capacitance of the tube, indicated by the dotted condenser 20, remains small and constant. Our invention may therefore be conveniently applied to such a tube by the simple introduction of an inductance 30 in series with the input circuit of the tube, the inductance being preferably of such a magnitude as will series resonate with the capacitance 20 at the high end of the working frequency range.

When our invention is applied to a tube following an amplifier tube the series resonant shunt placed across the output circuit of the amplifier tube decreases the output impedance of the amplifier tube and therefore tends to decrease the gain in the amplifier tube itself. This decrease in gain is far more than compensated for by the increase in potential applied to the control electrode of the second tube by the use of our invention. However, if the amplifier tube has an output impedance which is of the optimum value for maximum amplification the relative or percentage increase in gain obtained by the practice of our invention is much less than when the amplifier tube has an output impedance less than the optimum so that the initial gain is not very large. For example, with an amplifier tube having the optimum output impedance the gain at the high frequencies might be increased say 20%, whereas with an amplifier tube having an output

impedance which is low relative to the optimum, the gain might be increased two-fold or three-fold. Our invention may therefore most advantageously be applied to amplifier circuits in which the output impedance is less than the optimum.

In the case of screen grid tubes the anode to cathode resistance is very high, say of the order of 100,000 ohms. The external shunt capacitance on the plate is also high, being of the order of 10 to 15 micro-microfarads, which tends to reduce the effective external impedance. The optimum impedance should be at least comparable with the tube impedance, and this high impedance it is practically impossible to attain without utilizing an efficient tuned circuit. In the case of an untuned screen grid amplifier the output circuit impedances are therefore less than the optimum value, and to such an amplifier my invention may be applied with a substantial overall increase in gain.

By way of illustration Fig. 5 of the drawing shows an untuned cascade screen grid amplifier. This amplifier comprises tubes 60, 62, and 64, followed by a detector tube 66. Tubes 60, 62, and 64 have constant apparent input capacitances because of the shielding effect of the screen grid employed in the tubes. Tube 66 has a constant apparent input capacitance because of the negligible shunt impedance of the output filter section 68 for radio frequencies. The tubes are coupled by fixed transformers 70, 72, and 74, and these being untuned are low in impedance relative to the tube impedance, the screen grid tubes having a very high anode to cathode resistance.

Under these circumstances each of the tubes may especially advantageously be provided with additional series inductances, numbered 30, which in each case are preferably suitably dimensioned to series resonate with the apparent tube input capacitance at a desired frequency. If the transformers are naturally resonant to a frequency in the middle of the range a drop in amplification at the high frequencies may be avoided by the use of our invention, though a drop at low frequencies will still remain. If it is desired to obtain a substantially level amplification characteristic the transformers may be made naturally resonant to a frequency lower than the working frequency range. In such case there is decreasing amplification with increasing frequency over the entire range owing to the diminishing output impedance value with increasing frequency. Now, in accordance with our invention the inductance 30 may be made to series resonate with the apparent input capacitance of the tubes at the high frequency end of the range, thereby leveling out the gain curve. The percentage increase in gain obtained at the high frequencies is very substantial because for these

frequencies the output impedance of the transformers is quite low, the natural resonance frequency thereof being considerably departed from at the high frequencies.

In another aspect, the fact that the coupling impedance between the tubes should not be a very high impedance may be explained because the resonant rise in potential obtained across either of the two series resonant reactances is caused by a large current flow, and in order to permit free circulation or growth of this large current the impedance across which the series resonant circuit is connected must itself not be too high.

It will be observed that the input circuit of the tube 60 is connected across a variometer 76, in series with an antenna circuit 78, which is an effective capacitance, or in other words, that the input circuit of the tube 60 is connected across an inductively tuned circuit. This represents another type of circuit to which the present invention is especially advantageously applicable, for when dealing with inductively tuned circuits the efficiency of the circuits falls off at the higher frequencies, owing to the greatly reduced value of inductance employed, for the resonant rise in a tuned circuit is greater in a so-called stiff circuit, having a large ratio of inductance to capacitance for a given frequency. This principle may, of course, be applied to a cascade tuned amplifier when the tuned circuits are inductively rather than capacitively tuned.

The antenna circuit 78 is not a true capacitance, the antenna lead-in being equivalent to a series inductance 80. This inductance remains fixed and its presence necessitates that the variable inductance 76 be made especially small at high frequencies, which aggravates the looseness of the coupling of tube 60 to the antenna circuit, and increases the importance of our invention.

At this point it may not be amiss to point out one advantage in using bifilar or substantially unity coupling transformers as the coupling transformers 70, 72, and 74. Referring to Fig. 6, there is a tube 210, the output circuit of which is coupled to the input circuit of a tube 212 by means of a transformer 214. This transformer is assumed to have leakage which is represented in the present case by an equivalent diagram including series inductances 216 and 218. The transformer is shunted by associated capacitance so that at high frequencies the coupling is weakened further than at low frequencies. Our invention may be applied to circuits including transformers with less than unity coupling in order to overcome this difficulty, although certain troubles may arise which are subsequently pointed out, but unity coupling is preferred in order to avoid the said troubles and the aggravated looseness of coupling at high frequencies which is caused by

the presence of leakage in the transformer.

In Fig. 7 we have illustrated the application of our invention to a vacuum tube following an automatically tuned amplifier stage. The tube 82 is any tube having a constant apparent input capacitance, represented by the dotted condenser 20, and it may, for example, be a detector tube, as in Fig. 1, or a reactionless link tube, as in Fig. 2, or 10 a screen grid tube, as in Fig. 4. Tube 82 is preceded by an amplifier tube 84 having an output transformer 86 which is naturally resonant in circuit to a frequency lower than the frequency range over which the stage is 15 to be automatically tuned. Frequencies in the working frequency range are therefore higher, and for them the output circuit of tube 84 is effectively capacitive and characterized by a decreasing impedance with increasing frequency, thereby causing decreasing gain and decreasing alternating potential on the anode of tube 84 with increasing frequency, which in turn causes a reduction in the apparent input capacitance of the tube, 20 represented by the dotted variable condenser 88. Condenser 88 is automatically variable in the proper sense for automatic tuning, and the input transformer 90 is selected to be naturally resonant in circuit with the variable capacitance 88 for the desired frequency range.

Obviously, the range of frequency to which such an automatically tuned stage may be kept in tune depends largely upon the 25 range of variation obtainable in the apparent input capacitance 88. In accordance with our invention an inductance 30 is connected in series with the input circuit of the tube 82, and is so proportioned as to series resonate with the apparent input capacitance 20 of the tube 82 at the high frequency end of the range. This results not only in a gain in potential applied to the control electrode of tube 82, but the series resonant shunt 30 across transformer 86 greatly reduces the impedance thereof at the high frequency end of the range, thereby greatly reducing the alternating anode potential on tube 84, which in turn causes a reduction in the apparent input capacitance 88, thereby increasing the 35 range of capacitance available for automatic tuning, and so increasing the frequency range of the automatically tuned amplifier stage.

In Fig. 8 we have plotted two curves showing amplification as a function of wave length. This amplification is measured in terms of the ratio of the potential across the input circuit of the tube having the series inductance 30 to the potential across the input circuit of the preceding tube. For example, in Fig. 7 of the drawing the amplification would be measured by the ratio of the potential between the control electrode and cathode of tube 82 to the potential be-

tween the control electrode and cathode of tube 84. The dotted curve A in Fig. 8 shows how the gain falls off at the higher frequencies, in the absence of a series inductance such as we have described, while curve B shows the improvement in gain obtained when using such a series inductance. Curve B is substantially level, and shows the marked increase in gain obtained at the high frequencies, and at the same time illustrates that 70 there is some additional gain even at the low frequencies, for although series resonance is then departed from there is still some resonant potential rise.

It should be observed that the improvement indicated by curve B does not include the gain due to the better automatic tuning of tube 84 in Fig. 7, for the comparison is made between potentials existing beyond the tuned input circuit of tube 84. The gain 80 shown is therefore that obtainable by the use of series resonance in the input circuit of tube 82 when using a coupling means which is not a very high impedance, for the resonance frequency of transformer 86 is considerably departed from at the high frequency end of the range.

An automatically tuned stage such as is illustrated in Fig. 7 preferably employs bifilar wound transformers, that is, the coupling transformers 86 and 90 are bifilar wound or otherwise constructed to have substantially unity coupling, for this, in addition to maximum coupling, makes possible the obtention of a relatively smooth and gradually varying input capacitance curve, instead of an irregular curve having a number of inflection points.

It may be desired to still further improve the gain at the high frequency end of the range when using a circuit such as is illustrated in Fig. 7, or in fact, when using any circuit employing fixed coupling transformers which are bifilar wound or otherwise constructed to have substantially unity coupling. Referring to Fig. 9, the dotted curve C represents the apparent input capacitance variation of a tube such as the tube 84 in Fig. 7 when using a bifilar output transformer such as the transformer 86, and without using the inductance 30. A decreasing capacitance with decreasing frequency, as at the point 92, is caused by an inductive output circuit, having decreasing impedance with decreasing frequency. An inductive output circuit causes regeneration, and the region 92 is therefore a region of regenerative reaction. Increasing capacitance with decreasing frequency, as at the point 94, is caused by increasing output impedance with 115 decreasing frequency, indicating that the output circuit is capacitive. A capacitive output circuit causes degenerative reaction, and therefore the region 94 is a region of degenerative reaction. An inflection point such 120

110

115

120

125

130

as the point 96 has zero slope and represents a frequency at which the output circuit is neither capacitive nor inductive, but rather is resonant or resistive, and at such a point there is neither regenerative or degenerative reaction.

When the inductance 30 is added in the input circuit of tube 82 the input capacitance curve is changed from the simple dotted curve C to the more complex solid line curve D, which has an additional peak caused by the resonant shunt 30, 20. The region 96, like the region 94, is degenerative. The inflection point 98, like the inflection point 96, is a point of neither regenerative nor degenerative reaction. The region 100, like the region 92, is regenerative in reaction. For automatic tuning of the input circuit of an amplifier tube there must be increasing capacitance with decreasing frequency, so that regions 94 or 96 may be utilized for automatic tuning. By adjusting the constants of the circuits so as to locate the inflection point 98 at the high frequency end of the range the gain at that end of the range may be improved because of the absence of damping or degeneration at this point, and in fact, if desired the inflection point 98 may be moved slightly further toward the low frequency end of the range so as to obtain a slight regeneration at the high frequency end of the range, which further improves the gain. It will be understood that if desired, when the inductance 30 is added to the succeeding input circuit, the constants of the circuit may be so chosen that the inflection point 98 is at a frequency higher than the range. Automatic tuning will then take place over the portion 96 only of curve D, and there will be no regenerative reaction throughout the range, just as though no inductance 30 were employed.

In Fig. 10 we have illustrated a radio receiver embodying various features of our invention. This receiver comprises an antenna circuit 102, the energy collected by which is fed to a selector 104 having variable circuit constants, after which the energy of selected frequency is amplified in a radio frequency amplifier 106, having fixed circuit constants, the amplifier energy being detected in a suitable detector 108, from which the rectified energy may be fed to an audio frequency amplifier and a reproducer in the conventional manner. This general arrangement of pre-selection in tuned circuits followed by amplification in an amplifier having fixed circuit constants is set forth in a copending application of Lester L. Jones, Ser. No. 205,934, filed July 15, 1927, while the particular form of radio frequency amplifier here set forth, which consists of a plurality of either single or multi-stage automatically tuned amplifiers separated by reactionless link stages is set forth in our copending application, Ser. No. 403,161, filed October 29, 1929.

Referring to the wiring diagram of Fig. 10, the selector 104 is followed by a reactionless link stage 110, which may be designed in accordance with the teachings of the copending application Ser. No. 397,632, previously referred to in connection with Fig. 2, or may be a screen grid tube, as disclosed in our copending application Ser. No. 403,161, filed October 29, 1929, and which is designed to prevent reaction from the amplifier 106 upon the selector 104. The link stage 110 is followed by an automatically tuned amplifier 112. This may consist of one or more tubes or stages arranged in cascade and designed for automatic tuning over the entire frequency range, in accordance with the teachings in the copending application Ser. No. 397,633, already referred to.

As is set forth in our copending application Ser. No. 403,161, supra, if further amplification is desired it is not feasible to cascade directly upon an automatically tuned amplifier such as the amplifier 112, another and similar automatically tuned amplifier, such as the amplifier 114, each being tuned over the full frequency range, but it is possible to do so provided the automatically tuned amplifiers 112 and 114 are linked by a stage, such as the link stage 116, characterized by a constant apparent input capacitance. In the case of the stage 116 the tube 118 therein is given a constant apparent input capacitance by a complex output circuit similar to that described in connection with Fig. 2 of the drawings. It will be noted that link stage 116 is similar to the circuit shown in Fig. 2 except that the input or long wave transformer 120 is shown astatically wound in four sections, while the output or short wave transformer 122 is astatically wound in two sections, in accordance with the teachings of the copending application of Lester L. Jones, Ser. No. 402,379, filed October 25, 1929.

In accordance with the present invention the inductance 30 is connected in series with the input circuit of tube 118, and is made of suitable magnitude to series resonate with the apparent tube input capacitance thereof. Transformers 120 and 122 are preferably bifilar wound in order to prevent irregular inflection points in the reaction and capacitance curves of the circuits, and the sections of the transformers are dimensioned to be naturally resonant to a frequency higher than the frequency range in order to avoid inflection points which would be caused by high impedance due to resonance within the working frequency range. Such resonance points would be especially injurious when employing a series input inductance such as the inductance 30 because the successful operation of the series resonant shunt requires the flow of large currents which would be prevented

5 by resonance and concomitant high impedance in the coupling transformer. The inductance 30 is itself astatically wound in order to prevent magnetic coupling with other circuits.

10 The automatically tuned amplified 114 may, if further amplification is desired, be followed by an additional automatically tuned amplifier 124, and stages 114 and 124 should also be separated by a link stage characterized by constant apparent input capacitance, exemplified in this case by a screen grid link stage 126. This stage is similar to that described in connection with Fig. 4 of the 15 drawings, and is similar to the link stage 116 except that the constant apparent input capacitance of the tube is obtained by reason of the screen grid instead of by the use of a complex output circuit. As before, the input and 20 output transformers 128 and 130 are preferably bifilar wound, and they, as well as the series inductance 30, are astatically wound, transformer 128 being wound, if necessary, in four sections in order to prevent resonance 25 within the working frequency range.

30 The automatically tuned stage 124 is in this case illustrated as having only a single stage. The input circuit thereof is provided with a series inductance 30, as in Fig. 3 of the present application, inductance 30 series resonating with that value of apparent input capacitance of the tube which it has at the high frequency end of the range, in order to boost the gain at that point.

35 The automatically tuned amplifier 124 is followed by the detector stage 108, and this is characterized by constant apparent input capacitance by reason of the output circuit being shunted for radio frequencies by shunt condensers, as in the filter section 6. The detector stage 108 is similar to that set forth in Fig. 1 of the drawings, except that the input transformer 132 and the series inductance 30 are shown to be astatically wound, transformer 132 being wound in four sections to prevent resonance within the working 40 frequency range.

45 By using the inductance 30 in the detector stage the tuning range of the amplifier stage 124 may be considerably broadened, as was previously explained in connection with Figs. 7 and 9 of the drawing. Ordinarily it is therefore not necessary to additionally use the inductance 30 in the input circuit of the automatically tuned stage, as is shown in the amplifier 124. However, it is perfectly feasible to employ both inductances in order to boost the gain at still higher frequencies, but in such case the precaution must be observed 50 of staggering or making somewhat different the resonance frequencies of the two series resonant circuits, for otherwise oscillation may be set up.

55 In general, it may be mentioned that the series inductance 30 should have small dis-

tributed capacitance, that is, it should be substantially inductive. The reason for this is that the resonant rise in potential varies inversely as the decrement or directly as the so-called stiffness of the circuit, and this 60 requires as large a ratio as possible of inductance to capacitance. The effective inductance of an inductance shunted by a capacitance is increased, and therefore the ratio of the inductance 30 to the apparent input capacitance 20 would be decreased by capacitance in shunt with inductance 30. Also, if the inductance 30 consists of a low inductance shunted by capacitance, instead of a high 65 substantially pure inductance, the inductance value falls off rapidly at the low frequency end of the range, thereby spoiling the gain in that region.

70 The inductance 30 is made resonant with the apparent input capacitance 20 at the high frequency end of the range not only because in most cases that is where the extra gain is needed, but also because it is only with this arrangement that improved gain may 75 be obtained over the entire frequency range. If inductance 30 were made series resonant with capacitance 20 at the low frequency end of the range some gain would be obtained at low frequencies, but at high frequencies inductance 30 would act as a choke and severe 80 loss would result. When inductance 30 is made series resonant with capacitance 20 at the high frequency end of the range, at low frequencies inductance 30 is of reduced reactance, and not only does not diminish the 85 gain, but, as was illustrated by curve in Fig. 8, somewhat increases the gain.

90 The transformers should preferably be coupled with substantially unity coupling, as by the use of bifilar winding, because leakage flux is equivalent to series inductance in both the primary and secondary circuits, and series inductance in the secondary circuit may be too great to permit the obtention of 95 series resonance with the inductance 30. On the other hand there may occur high impedance peaks at some frequencies which will prevent the desired circulating current when using the series resonant shunt circuit. Of course, when using automatically tuned 100 stages it is anyway desirable to have substantially unity coupling transformers in order to simplify the design of the automatically tuned stages. In general, it is desirable and simple to have transformers 105 which have impedances which vary smoothly with frequency, and which do not have resonance points within the working frequency range.

110 From the foregoing description it will be understood that our invention is applicable to almost any vacuum tube circuit, and very conveniently applicable to those in which the input capacitance of the tube is substantially 115 constant, such as a detector tube, or a tube 120

made reactionless by a special output circuit, or a screen grid tube. It will also be understood that our invention is advantageously applicable to a cascade amplifier of the un-
5 tuned type, of the automatically tuned type, and of the inductively tuned type. When used with the automatically tuned type of amplifier the gain may be very much increased at the high frequency end of the
10 range by elimination of degeneration, and if desired, by the introduction of regeneration, at the high frequencies.

It will be apparent that while we have shown and described our invention in the
15 preferred forms, many changes and modifications may be made in the circuits disclosed without departing from the spirit of the invention, defined in the following claims.

We claim:

20 1. In the operation of an automatically tuned amplifier stage, the method of increasing the range of automatic tuning which includes shunting the output circuit of the automatically tuned stage by a series circuit
25 of inductance and capacitance of proper relative magnitude to series resonate at the high frequency end of the range.

2. In the operation of an automatically tuned amplified stage having an output circuit coupled to a succeeding input circuit by a substantially unity coupling, the method of reducing the damping in the input circuit of the automatically tuned stage at the high frequency end of the range which includes
35 shunting the secondary of the output circuit by a series circuit of inductance and capacitance of proper relative magnitude to series resonate at the high frequency end of the range and adjusting the resulting inflection
40 point in the input capacitance curve of the amplifier to be at the high frequency end of the frequency range.

3. A radio circuit comprising an electron emission tube, an output circuit therefor including a regenerative feed back inductance and a degenerative feed forward resistance arranged to prevent reaction through the tube, and an input circuit therefor comprising coupling means and an additional inductance connected in series therewith between the coupling means and the tube.

4. A radio circuit comprising a screen grid electron emission tube, and an input circuit therefor comprising bifilar wound trans-
55 former coupling means and an additional inductance connected in series with the secondary thereof between the secondary and the control electrode of the tube.

5. A radio circuit for operation over a range of radio frequencies comprising an electron emission tube and an input circuit therefor comprising coupling means and an additional inductance connected in series between the coupling means and the following tube, said inductance being of suitable mag-

nitude to series resonate with the apparent tube input capacitance at the high frequency end of the frequency range.

6. A radio detector circuit for operation over a range of frequency comprising a detector tube and an input circuit therefor comprising coupling means and an additional inductance connected in series between the coupling means and the following tube, said inductance being of suitable magnitude to series resonate with the apparent tube input capacitance of the detector tube at the high frequency end of the frequency range.

7. A radio circuit for operation over a range of radio-frequencies comprising an electron emission tube, an output circuit therefor including a regenerative feed back inductance and a degenerative feed forward resistance arranged to give the tube a substantially constant apparent input capacitance, and an input circuit therefor comprising coupling means and an additional inductance connected in series between the coupling means and the following tube, said inductance being of suitable magnitude to series resonate with the apparent tube input capacitance at the high end of the frequency range.

8. A radio circuit for operation over a range of radio frequencies comprising a screen grid electron emission tube, and an input circuit therefor comprising coupling means and an additional inductance connected in series between the coupling means and the following tube, said inductance being of suitable magnitude to series resonate with the apparent input capacitance of the tube at the high end of the frequency range.

9. A radio circuit for operation over a range of radio frequencies comprising an electron emission tube, an input circuit therefor including coupling means and an additional inductance arranged in series therewith between the coupling means and the tube, and an output circuit arranged to automatically tune the input circuit, the additional inductance in the input circuit being of suitable magnitude to series resonate with the apparent tube input capacitance at the high end of the frequency range.

10. A radio circuit for operation over a range of radio frequencies comprising an amplifier tube having an output circuit the impedance of which is less than the optimum impedance for maximum amplification, a second vacuum tube, and an input circuit therefor comprising means coupled to the output circuit of the amplifier tube and an additional inductance connected in series between the coupling means and the second tube, said inductance being of suitable magnitude to series resonate with the apparent tube input capacitance of the second tube at the high frequency end of the frequency range.

11. A radio circuit for operation over a

range of radio frequencies comprising an amplifier tube having an output circuit the impedance of which is less than the optimum impedance for maximum amplification, a 5 detector tube, and an input circuit therefor comprising means coupled to the output circuit of the amplifier tube and an additional inductance connected in series between the coupling means and the detector tube, said 10 inductance being of suitable magnitude to series resonate with the apparent tube input capacitance of the detector tube at the high frequency end of the frequency range.

12. A radio circuit for operation over a 15 range of radio frequencies comprising an amplifier tube having an output circuit the impedance of which is less than the optimum impedance for maximum amplification, another vacuum tube, an output circuit therefor including a regenerative feed back inductance and a degenerative feed forward resistance arranged to give the tube a substantially constant apparent input capacitance, and an input circuit therefor comprising means coupled to the output circuit of the amplifier tube, and an additional inductance connected in series between the coupling means and the second tube, said inductance being of suitable magnitude to series 25 resonate with the apparent tube input capacitance of the second tube at the high frequency end of the frequency range.

13. A radio circuit for operation over a 30 range of frequency comprising an amplifier tube having an output circuit the impedance of which is less than the optimum impedance for maximum amplification, a screen grid tube, and an input circuit therefor comprising means coupled to the output circuit of the amplifier tube, and an additional inductance of suitable magnitude to series resonate with the apparent tube input capacitance of the screen grid tube at the high frequency end of the frequency range.

45 14. A radio circuit for operation over a range of radio frequencies comprising an amplifier tube having input and output circuits so arranged that the output circuit automatically tunes the input circuit over the 50 frequency range, a second vacuum tube, and an input circuit therefor comprising means coupled to the output circuit of the amplifier tube, and an additional inductance connected in series between the coupling means and the 55 second tube, said inductance being of suitable magnitude to series resonate with the apparent tube input capacitance of the second tube at the high frequency end of the frequency range.

60 15. A radio circuit for operation over a range of radio frequencies comprising an amplifier tube having input and output circuits so arranged that the output circuit automatically tunes the input circuit over the frequency 65 range, a detector tube, and

an input circuit therefor comprising means coupled to the output circuit of the amplifier tube, and an additional inductance connected in series between the coupling means and the detector tube, said inductance being of suitable magnitude to series resonate with the apparent tube input capacitance of the detector tube at the high frequency end of the frequency range. 70

16. A radio circuit for operation over a range of radio frequencies comprising an amplifier tube having input and output circuits so arranged that the output circuit automatically tunes the input circuit over the frequency range, a second vacuum tube, an output circuit therefor including a regenerative feed back inductance and a degenerative feed forward resistance arranged to give the tube a substantially constant apparent input capacitance, and an input circuit therefor comprising means coupled to the output circuit of the amplifier tube, and an additional inductance connected in series between the coupling means and the second tube, said inductance being of suitable magnitude to series resonate with the apparent tube input capacitance of the second tube at the high frequency end of the frequency range. 75 80 85

17. A radio circuit for operation over a range of frequency comprising an amplifier tube having input and output circuits so arranged that the output circuit automatically tunes the input circuit to the received frequency, a screen grid tube, and an input circuit therefor comprising means coupled to the output circuit of the amplifier tube, and an additional inductance of suitable magnitude to series resonate with the apparent tube input capacitance of the screen grid tube at the high frequency end of the frequency range. 90 95 100

18. A radio circuit for operation over a range of frequency comprising an amplifier tube having input and output circuits so arranged that the output circuit automatically tunes the input circuit over the frequency range, a second vacuum tube characterized by a constant apparent input capacitance, and an input circuit therefor comprising means coupled to the output circuit of the amplifier tube, and an additional inductance of suitable magnitude to series resonate with the apparent tube input capacitance of the second tube at the high frequency end of the frequency range, in order to increase the range of capacitance change and the range of automatic tuning of the input circuit of the first tube. 105 110 115 120

19. A radio circuit for operation over a range of frequency comprising an amplifier tube having input and output circuits so arranged that the output circuit automatically tunes the input circuit over the frequency range, a second vacuum tube characterized 125 130

by a constant apparent input capacitance, and an input circuit therefore comprising means coupled to the output circuit of the amplifier tube, and an additional inductance of suitable magnitude to series resonate with the apparent tube input capacitance of the second tube at the high frequency end of the frequency range, in order to decrease the damping in the input circuit of the first tube.

20. A radio circuit for operation over a range of frequency comprising an amplifier arranged to be automatically tuned over the range of frequency, a second amplifier arranged to be automatically tuned over the range of frequency, a link stage for coupling the amplifiers in cascade, said link stage including a vacuum tube characterized by a constant apparent input capacitance, and an input circuit therefore comprising coupling means and an additional inductance of suitable magnitude to series resonate with the apparent tube input capacitance at the high frequency end of the frequency range.

21. A radio circuit for operation over a range of frequency comprising an amplifier arranged to be automatically tuned over the range of frequency, a second amplifier arranged to be automatically tuned over the range of frequency, a link stage for coupling the amplifiers in cascade, said link stage including a vacuum tube characterized by a constant apparent input capacitance, and an input circuit therefore comprising coupling means and an additional inductance of suitable magnitude to series resonate with the apparent tube input capacitance at the high frequency end of the frequency range, a detector tube coupled to the second automatically tuned amplifier, and an additional inductance of suitable magnitude to series resonate with the apparent tube input capacitance of the detector tube at the high frequency end of the frequency range.

22. A radio circuit for operation over a range of frequency comprising an amplifier tube having an input circuit including coupling means and an additional inductance arranged in series therewith, and an output circuit arranged to automatically tune the input circuit, a second vacuum tube, and an input circuit therefore comprising means coupled to the output circuit of the first tube and an additional inductance connected in series therewith, said additional series inductances being arranged to series resonate with the apparent tube input capacitances of the tubes at different frequencies near the high end of the frequency range.

23. The combination with an electron emission tube and associated circuits arranged to cause the tube to have a substantially constant apparent tube input capacitance over a range of radio frequencies, of an input circuit for the tube including coupling means and an additional inductance connect-

ed in series therewith and in series with the tube input electrodes, said inductance being of suitable magnitude to series resonate with the apparent tube input capacitance at the high end of the frequency range.

24. A radio circuit comprising an electron emission tube, and an associated input circuit including a bifilar wound coupling transformer, and an additional inductance connected in series between the transformer and the tube input electrodes, said inductance being of proper magnitude to series resonate with the apparent tube input capacitance at a desired frequency.

25. A radio circuit comprising an electron emission tube, and an associated input circuit including a coupling transformer the primary and secondary of which are coupled with a coupling substantially equal to unity, and an additional inductance connected in series between the transformer and the tube input electrodes, said inductance being of proper magnitude to series resonate with the apparent tube input capacitance at a desired frequency.

26. A radio circuit comprising an electron emission tube, and an associated input circuit including a coupling transformer the impedance of which varies smoothly with changes in frequency within the working frequency range, and an additional inductance connected in series between the transformer and the tube input electrodes, said inductance being of proper magnitude to series resonate with the apparent tube input capacitance at a desired frequency.

27. A radio circuit comprising an electron emission tube, and an associated input circuit including a coupling transformer which does not have a resonance point within the working frequency range, and an additional inductance connected in series between the transformer and the tube input electrodes, said inductance being of proper magnitude to series resonate with the apparent tube input capacitance at a desired frequency.

28. A radio circuit comprising an electron emission tube, and an associated input circuit including a coupling transformer which is bifilar wound and subdivided into sections dimensioned to be naturally resonant to frequencies higher than the working frequency range, and an additional inductance connected in series between the transformer and the tube input electrodes, said inductance being of proper magnitude to series resonate with the apparent tube input capacitance at a desired frequency.

29. A radio circuit comprising an electron emission tube, and an associated input circuit including coupling means the impedance of which is relatively low, and an additional inductance connected in series between the transformer and the tube input electrodes,

said inductance being of proper magnitude to series resonate with the apparent tube input capacitance at a desired frequency, the impedance of said coupling means being sufficiently low to permit the building up of large circulatory currents through the resulting series resonant circuit.
